UNITED STATES PATENT OFFICE

2,504,513

ELECTRIC CIRCUIT BREAKER

William J. Fleming, New Britain, Conn., assignor
to The Trumbull Electric Manufacturing Com-
pany, Plainville, Conn., a corporation of Con-
necticut

Application December 24, 1948, Serial No. 67,109

5 Claims. (CL 200—116)

1

My invention relates to electric switches or breakers of the type shown in the Von Hoorn Patent 2,150,013.

One object is to provide means for ensuring adequate pressure between the contacts.

Another object is to simplify the construction of such a switch.

Another object is to provide means for insuring quick and effective opening of the circuit.

Another object is to provide a switch or breaker in which the opening force varies in proportion to the variation in contact pressure.

The accompanying drawings and the following specification and claims will set forth one form of my invention.

Fig. 1 is a longitudinal sectional view showing in full lines the position of the parts when tripped automatically.

Fig. 2 is a similar view with the parts in the closed circuit position in full lines and in the reset position in dotted lines.

Fig. 3 is a cross-sectional view taken on the plane of the line 3—3 of Fig. 2.

The mechanism is shown mounted in a housing consisting of a base or body portion 7 and a cover 8. The circuit terminals 9 and 10 are mounted at opposite ends of the body. The switch contacts 11 and 12 are mounted in the body, contact 12 being carried by a movable arm 13 and contact 11 being flexibly mounted for instance on a flexible strip 14 connected to terminal 10.

The arm 13 is electro-conductive and has a hinge pin 15 guided in slots 16 in opposite sides of the body. This arm carries the contact 12 at one end and has a tip 17 at the other end normally supported by a shoulder 18 in the bimetal current actuated strip 19 which is supported by a bracket 20 connected to terminal 9 and adjustable by a screw 21 which is supported by a member 22.

The lower end of strip 19 is connected by a flexible conductor 23 to the adjacent end of the switch arm 13 so that when the switch arm is in the closed circuit position of Fig. 2 current can flow from 9 to 20, 19, 23, 17, 12, 11 and 14 to 10.

The manual operator 24 is pivoted at 25 and has shoulders 26 and 27 to engage the upper surface of arm 13. Operator 24 has a yoke 28 connected to swing with it and its lower end engages beneath arm 13 at 29 in the position of Fig. 2 at 30 in the full line position of Fig. 1 and at 31 when in the dotted position of Fig. 2.

A spring 33 is interposed under compression between arm 13 and the left end of two-armed

tilting lever or rocker 34 which is pivoted at 35 in slot 36 in the base.

In the position of Fig. 2, the spring 33 presses the right hand end of the switch arm 13 upward against the lower end of operator 24 and biases the left end of arm 13 downwardly against the catch shoulder 18 of the bimetal strip. At the same time, the spring is biasing lever 34 anti-clockwise so that its right hand end presses upwardly beneath the movable contact 11.

In case of an overload sufficient to warp strip 19 away from the tip 17 of arm 13, the arm will be suddenly tripped to the position of Fig. 1 under the impulse of spring 33 which will tilt the operator 24 to the position of Fig. 1 where the lower end of extension 28 will turn into the notch 38.

When the bimetal has cooled sufficiently the switch arm may be reset to the position of dotted lines in Fig. 2 by turning the operator 24 so that the extension 28 will raise the left hand end of the arm into latching position. The circuit can then be closed by turning the operator back to the position of Fig. 2 during which movement the shoulder 26 of the operator will press downwardly on the switch arm and tilt the arm against the spring 33. As the spring is compressed it tilts lever 34 and raises contact 11 until the contact 12 engages and presses it downward by the force applied to arm 13 by operator 24. In this position, the spring presses the lever 34 upwardly against strip 14 and thus applies pressure of contact 11 against 12. In this way the single spring 33 serves to press the contacts together in closed circuit position and also biases the main switch arm to the open circuit position when it is released by the bimetal latch or when the operator 24 is turned to the OFF position.

As the flexibly mounted contact in effect tilts or rotates about one edge during opening of the circuit there is a prying action. The more you increase contact pressure, the more you increase the force tending to move the contact 12 to the open position.

I claim:

- 45 1. In a circuit breaker, a switch arm, a current-actuated latch for supporting one portion of said arm, a movable contact for supporting a remote portion of said arm, a pivoted operator for engaging an intermediate portion of said arm and pressing said arm against said latch and against said contact in a closed circuit condition and a spring-actuated pivoted rocker pressed by the action of said operator and by said switch arm and pressing said contact against said arm.
- 50 2. In a circuit breaker, a tilting switch arm, a

current-actuated latch for supporting one portion of said arm, a movable contact for supporting a remote portion of said arm, a pivoted operator engaging an intermediate portion of said arm and pressing said arm against said latch and against said contact in a closed-circuit condition, a pivoted rocker having two arms and a spring interposed between one of said rocker arms and said switch arm, the other rocker arm pressing said contact against said switch arm.

3. In a circuit breaker, a switch arm, a current-actuated latch for supporting one portion of said arm, a movable contact for supporting a remote portion of said arm, a pivoted operator for engaging an intermediate portion of said arm and pressing said arm against said latch and against said contact in a closed-circuit condition and means including a pivoted rocker having two arms and a spring interposed between one of said rocker arms and said switch arm, the other rocker arm pressing said contact against said switch arm.

4. A circuit breaker including an insulating base, a contact movably supported in the base, a movable switch arm having a contact at one end for coacting with said movably supported contact, a current-actuated latch coacting with the other end of said arm, a spring supporting said arm,

a manually actuated operator for pressing said switch arm into latching engagement with said current-actuated latch and into circuit-closing engagement between said contacts and a member pivoted in the base and biased by said spring to press said movably supported contact toward the contact of the switch arm.

5. In a circuit breaker, a base, a floating switch arm, a pivoted support for said arm in said base, 10 a current-actuated latch coacting with said arm, a contact movably mounted in the base, an operating member for pressing said arm against said latch and said contact, a spring for retracting said switch arm upon an overload in the circuit and a rocker pivoted in the base and interposed between said spring and said contact for pressing said contact against said switch arm.
